Inventor:

Bernhard Lerden

By his Attorney

Charles K. Druse

UNITED STATES PATENT OFFICE.

BERNHARD LERDEN, OF VIENNA, AUSTRIA.

SPECTACLES WITH LIGHTING DEVICE.

Application filed June 1, 1925, Serial No. 34,190, and in Austria June 8, 1924.

This invention relates to spectacles provided with a lighting device. Spectacles with an annular reflector, the central looking opening forming a blind, are already known. According to the present invention the surface of the reflector is provided with 5 holders for removably supporting tubular incandescent lamps. This arrangement aims at a simple construction and enables the 10 lighting means to be replaced in a simple and cheap manner and permits the use of a larger or smaller number thereof as desired.

An embodiment of the invention is illustrated by the drawing, in which Fig. 1 is a 15 front view and Fig. 2 a cross section along the line A—B of Fig. 1.

The spectacles consist of two annular reflectors *c* connected together by a nose-bow or bridge and each provided with a concentric view opening *b*. The reflectors are of 20 U or channel shape in cross section, (Fig. 2) and serve as a blind, and are each provided on their end walls with a lining *i* of insulating material. Within the channel-shaped 25 reflectors are disposed holders *x* adapted removably to support tubular incandescent lamps *g*. The connecting wires may pass between the ring *c* and the lining *i* through the nose bow. Glass protecting rings *k* are

mounted in the open ends of the channel 30 members to protect the incandescent lamps *g*. The incandescent lamps are connected by flexible cords to any convenient source of electricity, such as a small battery or the like. 35

Claims:

1. A device of the character described, comprising a pair of bridge-connected annular members of channel shape in cross section, a plurality of pairs of lamp holders 40 secured in each of said annular members, and a tubular incandescent lamp removably supported in each pair of holders.

2. A device of the character described, comprising a pair of bridge-connected annular members of channel shape in cross section, a plurality of pairs of lamp holders secured in each of said annular members, a tubular incandescent lamp removably supported in each pair of holders, a glass ring 50 closing the open end of each of said channel members, a ring of insulating material mounted on the end wall of each of said members, and means for supplying current to said lamps. 55

In testimony whereof I have affixed my signature.

BERNHARD LERDEN.
